SPRAY HEAD

Elmer G. Munz, Detroit, Mich.

Application April 24, 1933, Serial No. 667,693

24 Claims. (Cl. 299—60)

This invention relates generally to irrigating apparatus and refers more particularly to spray equipment.

Although the present invention may be advantageously employed to improve the irrigating characteristics of the well known portable type of sprinkler, nevertheless, it finds particular utility when used in association with sprinkling systems embodying a group of spray heads either of the underground pop-up type or the stationary design to be more fully hereinafter set forth.

The advantages of the group systems over the portable type of sprinkler are indisputable, but the commercial application of the group system, especially for residential use, has sometimes been impractical due to the inability of the spray heads heretofore produced to operate efficiently on the relatively low water pressures available at the present time in many localities. In the past, it has sometimes been necessary to provide booster pumps or other devices for supplementing the available water pressure in localities where the pressure is relatively low before a sprinkling system could be installed with any degree of efficiency. Such practice has proven objectionable not only because the high cost of installation prohibited its use in the majority of cases, but also because the results secured from these installations were none too satisfactory.

It is, therefore, one of the principal objects of this invention to overcome the foregoing objection or, in other words, to render commercially practical the installation of sprinkling systems in localities having relatively low available water pressures without the necessity of supplementing these pressures by booster pumps or equivalent devices, and this is accomplished herein by providing a small capacity spray head constructed so as to effectively irrigate a relatively great area with the minimum amount of water pressure.

One of the features of this invention which contributes materially to the realization of the above object resides in constructing the head in such a manner that the latter insures uniform irrigation of the surrounding area by splitting up the water streams issuing from the head to such an extent that the area immediately adjacent the head will be effectively irrigated as well as the area remote from the head.

A further feature of the present invention which contributes materially to expediting installation as well as reducing the cost of manufacture to the minimum, resides in the provision of a spray head capable of being used in different localities having a wide range of pressure

variations. In other words, spray heads constructed in accordance with this invention are interchangeable and need not be specially built to suit the existing conditions at each installation.

A still further object of this invention is attributed to the extremely simple manner in which a spray head constructed in accordance with this invention may be fashioned to provide either a full circle spray or a part circle spray without the necessity of providing additional parts or interchanging any of the parts thereof.

In addition to the foregoing, the present invention contemplates obtaining all of the objects previously set forth as well as other objects with a spray head capable of being economically manufactured, assembled and installed.

The other features of this invention not specifically set forth above will become apparent as this description proceeds, especially when considered in connection with the accompanying drawings, wherein:

Figure 1 is an enlarged longitudinal sectional view through a spray head constructed in accordance with this invention;

Figure 2 is a sectional view taken on the line 2—2 of Figure 1 showing the serrations therein through which the water is discharged;

Figure 2a is a perspective view, partly in section, featuring a device for issuing a partial spray;

Figure 3 is a view similar to Figure 1 showing a slightly modified form of construction;

Figure 4 is also a view similar to Figure 1 showing a different form of spray head construction;

Figure 4a is a view similar to Figure 1 showing another modified construction;

Figure 5 is a view similar to Figure 1 showing a still further modification of the present invention;

Figure 6 is a plan view of a body portion of a spray head illustrating a different arrangement of serrations;

Figure 7 is a sectional view taken on the line 7—7 of Figure 3;

Figure 8 is a longitudinal sectional view through a sprinkling device showing one way in which the spray head may be slidably supported within a fitting embedded in the ground;

Figure 9 is a view similar to Figure 8 showing the installation of a stationary spray head;

Figure 10 is a sectional view showing the manner in which any one of the several embodiments of the invention may be employed as a portable unit.

Referring now more in detail to the several em-

bodiments of the invention shown herein for accomplishing the features set forth in the preamble of this specification and with special reference to Figure 1 of the drawings, it will be noted that I have illustrated in the latter figure a small capacity spray head 20 having a body portion 21 fashioned at the lower end for communication with a source of water under pressure and having an inwardly flared portion or dome 22 at the upper end thereof apertured as at 23 to provide for discharging the water from the body 21 of the head. The discharge of water through the aperture 23 in the head is controlled by a cap 24 having a stud 25 projecting into the body portion 21 and suitably anchored thereto. The lower portion 26 of the cap 24 is circular in cross section and is fashioned to engage an annular frusto-conical seat 27 surrounding the discharge opening 23 in the body. In the present instance, the adjoining bottom and side walls of the cap are arranged at right angles to each other so that a line contact is effected between the cap and seat 27.

The discharge of water through the opening 23 between the cap and seat 27 is effected herein by forming a plurality of circumferentially spaced passages or serrations 28 in the seat. As shown particularly in Figure 2, the serrations extend substantially radially with respect to the vertical center line of the body portion across the seat and may be formed in the seat at spaced intervals either entirely or only partially around the seat depending upon whether a full or a part circle spray is desired. In the event a part circle spray is desired, the serrations are extended only around the desired portion of the seat, and the remaining effective area thereof will be sealed by the line contact of the cap with the seat as shown in Figure 2a.

It will be apparent from the foregoing that the serrations 28 cooperate with the cap 24 to form orifices through which the water in the body 21 is discharged, and owing to the fact that the upper sides of the orifices are formed by the line contact of the cap with the seat, the water passing through the orifices instead of flowing in a well defined stream in the conventional manner will be broken up to such an extent that the area immediately surrounding the head will be irrigated as well as the area located at some distance from the head. This arrangement is extremely desirable since it provides for uniformly irrigating the area surrounding the head.

In actual practice, it has been found that merely providing a line contact between the cap and seat 27 is not extremely efficient in effecting the desired split-up of the streams emitting from the head when the latter is used in localities having relatively low pressures, and in order to increase the efficiency of the sprinkler when employed in localities of the above type, I provide means within the body of the head for causing the water to approach the orifices in a direction at an angle to the axes of the orifices. While any one of a number of different constructions may be resorted to for accomplishing the above feature, particularly satisfactory results are secured herein by resorting to the construction shown in Figure 3. It will be noted from the latter figure that the spray head 70 may be identical in construction to the spray head shown in Figure 1 with the exception that the cap 24' is secured in place upon the seat 27' of the body 21' by threading the stud 25' into a suitable core 30 anchored in the body 21' and having 75 passages 31 therethrough extending at an angle

to the normal flow of water through the body 21'. The construction is such that the water flowing from the source of supply must first pass through the inclined ports 31 in the core 30 before it is discharged through the orifices 28'. Inasmuch as the passages 31 extend at an angle to the normal flow of the water through the body 21', the passages effect a whirling action of the water adjacent the seat 27' and causes the water to be discharged into the orifices tangentially or at an angle with respect to the axes of the latter. The abrupt change in direction of the water as it enters the orifices 27' materially assists the line contact of the cap with the seat in splitting up the streams emitting from the orifices. 15

In view of the fact that whirling the water prior to discharging the same through the orifices effects to some extent a split-up of the streams emitting from the orifices, it is not absolutely essential to provide a line contact between the cap of the head and the conical seat on the body thereof. This is especially true in instances where higher pressures are available, and, accordingly, I have shown in Figure 4a a sprinkler 33 differing from the one shown in Figure 3 in that the head 34 is provided with a frusto-conical surface 35 corresponding in inclination to the seat 27'' so as to engage the same throughout substantially the entire effective area thereof. The seat 27'' has serrations 28'' similar to those shown in Figure 1 at 28 and in Figure 3 at 28'. In this connection, it is to be noted that if desired, serrations 35'' may also be formed in the surface 35 to register with the serrations 28'' in the seat 27'' as shown in Figure 4. 30

In Figure 5 of the drawings, I have shown another modified form of sprinkler designated by the reference character 36 having a body portion 37 similar in construction to the body portion 21 set forth in the first described form of the invention with the exception that the portion of the latter surrounding the opening 38 through the upper end thereof instead of having a conical seat formed thereon is fashioned to present an annular knife edge 39 for effecting a line contact with a conical seat 40 formed on the cap 41. In the present instance, the seat 40 is formed with serrations 42 for cooperation with the knife edge 39 to form the orifices through which the water is discharged from the body 37. As in the first described form of the invention, the line contact between the cap 41 and body acts to split the streams of water emitting from the orifices to irrigate the area immediately adjacent the head as well as the area spaced from the latter. The construction shown in Figure 5 may or may not be used in association with a core for effecting a whirling action of the water prior to discharging the same through the orifices depending entirely upon the available water pressure. However, I have shown in the above figure a core 43 identical in construction to the core 30 in that it forms a mounting for the cap 41 and serves to effect the desired whirling action of the water by means of the inclined passages 44 therethrough. 55

It should be noted that in the sprinkler head constructions shown in Figures 1, 2a, 3, 4, 4a and 5 there are two cooperating members which combine to form the water discharge passages of the head. One of these members is a seat and the other a cap. In each case, one of the two members has circumferentially spaced serrations therein, and the other member has an annular bearing therewith which serves to close the open side of the serrations forming discharge passages 70 75

of definite size. In Figure 4 both cooperating members are serrated and the registering serrations together form the discharge passages for the water. In the other figures, only one of the members is serrated, but this may either be the conical seat as shown in Figures 1, 3 and 4, or the cap member as shown in Figure 5. In Figures 1, 3 and 5 there is an annular line contact between the seat and the cap, but in Figures 4 and 4a the annular contact has a substantial radial width of area. It should also be noted that in each of the constructions the annular contact between the members is of less width than the width of the cooperating member which extends outwardly 15 furtherest in the direction of discharge. In Figures 1, 3, 4 and 5 the width of the annular contact is less than the length of the serrations, while in Figure 4a the width of the contact is less than the width of the conical cap member. The projection of the serrated or unserrated cooperating member radially beyond the annular contact between the members is an important feature of my invention, contributing to the breaking up of the streams to irrigate the area between the streams 20 within the outer boundary of the irrigated area.

In each of the foregoing embodiments of the invention, reference has only been made to a construction wherein the axes of the serrations in the seat extend radially with respect to the vertical center line of the spray head, and while this particular arrangement of serrations is satisfactory when employed in the manner shown by each of the foregoing modifications to break or split up the streams issuing from the serrations, nevertheless, when the available water pressure is extremely low, it may be desirable to accentuate the action of the various means previously set forth in connection with the foregoing modifications to split up the streams issuing from the spray head. This is accomplished herein by changing the angle of inclination of the serrations with respect to the direction of water flow in the spray head prior to entering the serrations. Serrations formed in accordance with the above are shown in Figure 6 by the reference character 45, and as will be observed from this figure, the axes of the serrations 45, instead of extending radially across the seat as in the construction shown in Figure 2, are inclined with respect to radial lines passing through the vertical axis of the spray head. Inclining the serrations in the manner set forth in Figure 6 relative to the direction of flow of the water in the spray head prior to entering the serrations obviously effects a change in direction of the water as it is discharged through the serrations. The extent the direction of flow of the water is changed by the serrations depends upon the angle of inclination of the serrations relative to the flow of the water 50 in the spray head prior to entering the serrations, and inasmuch as the turbulence naturally increases as the change in direction of flow increases, it necessarily follows that inclining the serrations assists in splitting up the streams issuing therefrom. It will also be apparent from the above that different effects may be secured by changing the angles of inclination of the serrations with respect to the flow of water in the spray head prior to entering the serrations so 55 that variations in pressure or velocity of the available water supply in different localities may be compensated for by merely changing the angle of inclination of the serrations to suit the existing conditions. The above construction eliminates the necessity of specially designing spray

heads for each locality having different water pressures since it permits a standard type of spray head to be readily adapted to a particular installation by merely changing or in effect adjusting the angle of inclination of the serrations. By virtue of this arrangement, the cost of manufacture and installation of spray heads constructed in accordance with this invention is materially reduced. Attention is called to the fact at this point that practically the same effect can be secured in the modifications shown in Figures 3 to 5, inclusive, by varying the cross sectional area of the passages through the core member, but this method of compensating for variations in velocity is not preferred herein since it would not only necessitate interchangeably mounting the cores in the spray head, but would also require the provision of a plurality of different types of cores.

In Figure 8 of the drawings, I have shown the manner in which any one of the above described forms of spray heads may be employed in association with an underground irrigating system wherein it is desirable to elevate the head above the ground by the action of the water. In detail, there is shown in Figure 8 a conduit 77 adapted to be embedded within the ground and having the lower end fashioned for attachment to a supply pipe (not shown). The upper end of the conduit 77 is open for receiving the body portion 18 of a suitable spray head, and the latter is slidably supported within the conduit by means of a vertically extending groove 79 formed in the inner wall of the conduit for engaging a projection 80 extending laterally outwardly from the lower end of the body 18 of the spray head. The spray head is secured in assembled relation to the body with the projection 80 in engagement with the groove 79 by means of a cap 81 threadedly mounted upon the upper end of the conduit 77 and having an inwardly extending shoulder 82 for engaging a correspondingly outwardly extending shoulder 83 on the lower end of the spray head body. The conduit 77 is preferably embedded in the ground to such an extent that the upper surface of the cap lies flush with the top surface of the ground, and the aforesaid upper surface of the cap is recessed as at 84 for receiving the cap member 85 on the spray head in such a manner that the top surface of the latter cap member forms a continuation of the corresponding surface of the cap member 81 when the spray head is in its lowermost position in the conduit. The construction is such that as soon as water under pressure is discharged into the conduit, the same will act upon the spray head to move the same from a position within the conduit to the position thereof shown in Figure 8 wherein the discharge orifices in the spray head are located an ample distance above the ground for effective 40 operation.

In Figure 9, I have shown a spray head constructed in accordance with any one of the above modifications as used in association with a stationary irrigating system. When it is desired to use any one of the above spray heads as an integral part of a stationary irrigating system, a suitable fitting 90 is secured to the upper ends of the spray heads in any convenient manner. The fittings 90 are provided with a laterally outwardly extending flange 91 and are centrally countersunk as at 92 for exposing the caps of the spray heads as well as the discharge orifices thereof. With this construction, the spray heads may be embedded within the ground to such an 50 55 60 65 70 75

extent that the top surface of the flange 91 lies substantially flush with the corresponding surface of the ground. When the spray heads are installed in this manner, the cap portions thereof are usually provided with a screw driver slot 93 so as to permit the caps to be readily removed for cleaning purposes.

The foregoing types of spray heads may also be employed with equal facility in association with a portable system and for accomplishing this result, the construction shown in Figure 10 may be provided. As shown, this construction is relatively simple and merely comprises a stand 95 having suitable legs 96 for engaging the ground 10 and having a central support 97 for attachment to the body portion 98 of a suitable spray head. In systems of this character, the water under pressure is usually supplied by a flexible hose, and the latter may be readily attached to the lower 15 end of the spray head in the usual manner (not shown herein).

From the foregoing description it will be apparent that my invention may be embodied in various modifications. In all of these devices, 25 however, there are certain underlying principles which have been combined for the first time in sprinkler apparatus.

In order to illustrate more specifically certain preferred apparatus coming within the purview 30 of my invention, I will refer again to the construction shown in Figures 1, 2 and 6 which represent a very desirable commercial form of the invention. For lawn sprinkling systems it is usual to employ heads having a certain predetermined capacity such, for example, as a head capable of discharging one gallon of water per minute. As a practical illustration of such a head it will be assumed that the dome 22 is arranged at 35 an angle of 45° and that the core 30 has formed 40 therein three inclined ports 31 equally spaced around the circumference. These ports, as shown in Figure 7 are obtained by milling notches 31 one-eighth inch wide and three thirty-seconds inch deep, the cutter being inserted tangentially of the disk. The serrations 28 extend 45 radially and are so proportioned in number and in size so that under a head of thirty-five pounds pressure in the nozzle, the amount of water discharged per minute will be one gallon. In one 50 practical commercial head the number of serrations is twenty. It is to be understood that the figures given above are only by way of example in order to illustrate the relationship of the several 55 variable factors which affect the distribution of the water. When the nozzle head described is operated at thirty-five pounds pressure, it has been found that a very satisfactory distribution is obtained, irrigating very uniformly a considerable area.

60 If the available water pressure instead of being thirty-five pounds is considerably less, say for example only fifteen pounds, a satisfactory distribution can not be obtained with the proportions given above, but the head may easily be adapted 65 for the reduced pressure by only a slight modification in the construction of the serrations. Instead of having the serrations extending radially, they are inclined in the opposite direction from the whirling water in the head at an angle of approximately 30°. It has been found that this 70 change in angle fully compensates for the reduction in pressure. On the other hand, if the available pressure is higher than thirty-five pounds, say sixty pounds, it has been found desirable to 75 incline the serrations in the same direction as the

whirling water at an angle of 30° with a radial line. For pressures intermediate fifteen and sixty pounds the serrations may be arranged at intermediate angles, it being understood that a certain degree of latitude may be allowed while obtaining satisfactory distribution.

As an alternative construction for operating at reduced pressures, the head designed for thirty-five pounds pressure may be used with the radial serrations by decreasing the size of the 10 openings 31 in the core, thereby causing the velocity of the whirling water above the core to be maintained at approximately the same speed as with the higher pressure. Similarly, a nozzle head with radial serrations may be used at sixty 15 pounds pressure by increasing the size of the openings 31 in the core until the velocity of the whirling water in the head is substantially the same as in the head of the portions first described. The effects of variable pressure may also be compensated for by modification of other factors, such as by changing the angle of the dome 22. By making this angle steeper, less whirl is obtained and by making the angle flatter, more 20 whirl is obtained. The proportions and figures given above are by way of illustration only.

It is to be noted that while in some of the broader aspects of the invention, the means for whirling the water may be eliminated, yet most of the modifications described employ this means in combination with a plurality of confined orifices arranged circumferentially of the whirling means and also arranged in a nonrotatable casing. This particular combination of elements 30 is particularly effective in causing proper distribution of the water with a very simple mechanical construction adapted for economical 35 commercial manufacture.

What I claim as my invention is:

1. A spray head having a body portion communicating at the lower end with a source of water under pressure and having an opening through the upper end surrounded by a conical seat formed with circumferentially spaced serrations across the same extending substantially to the point where the water leaves the spray head, means cooperating with the serrations to form orifices including a cap for said opening having a substantially line contact with said seat to break up the streams of water as they issue from the orifices, and means located within the body between the orifices and source of water under pressure to impart a whirling motion to the water prior to the latter entering the orifices.

2. A spray head having a body portion communicating at the lower end with a source of water under pressure and having an opening through the upper end thereof, means located within the body between the aforesaid ends for imparting a whirling motion to the water, a conical seat surrounding the opening in the upper end of the body formed with serrations therein inclined with respect to the direction of flow of the water prior to entering the serrations at an angle predetermined in accordance with the velocity of the water said serrations extending substantially to the point where the water leaves the spray head, and a cap for said opening cooperating with the serrations to form orifices.

3. A spray head having a body portion communicating at the lower end with a source of water under pressure and having an opening through the upper end thereof, means located within the body between the aforesaid ends for

imparting a whirling motion to the water, a conical seat surrounding the opening in the upper end of the body formed with serrations therein inclined with respect to the direction of flow of the water prior to entering the serrations at an angle predetermined in accordance with the velocity of the water said serrations extending substantially to the point where the water leaves the spray head, and means cooperating with the serrations to form orifices comprising a cap member for the opening having a substantially line contact with the conical seat to insure breaking up the streams of water as they issue from the orifices.

15 4. A spray head for lawn sprinkling systems and the like comprising a body, means for whirling the water in said body, said body being provided with a series of circumferentially spaced laterally extending grooves for projecting the water in a series of streams and said body also being provided with an annular edge having a substantially line contact with the grooved portion of said body, said grooves extending substantially to the point where the water leaves the spray head.

25 5. A spray head for lawn sprinkling systems and the like comprising a body, means for whirling the water in said body, said body being provided with a series of circumferentially spaced laterally extending grooves extending substantially to the point where the water leaves the spray head for projecting the water in a series of streams, said grooves being inclined at an angle with respect to the direction of whirl and said body being provided with an annular edge having a substantially line contact with the grooved portion of said body.

30 6. A sprinkling device comprising a stationary casing communicating with a source of water under pressure, a nozzle head longitudinally slideable in said casing, means within said nozzle head for whirling the water, said nozzle head being provided with a series of circumferentially spaced laterally extending grooves extending substantially to the point where the water leaves the nozzle head for projecting the water in a series of streams, said grooves being inclined at an angle with respect to the direction of whirl and said body being provided with an annular edge having a substantially line contact with the grooved portion of said body.

35 7. A sprinkling device comprising a body, means for whirling the water in said body, said body being provided with a series of circumferentially spaced grooves extending laterally from the axis of the whirl, a screw extending axially within said body and having a disk-shaped head engaging said grooves, a flange extending outwardly from said body having a portion extending upwardly beyond the head of said screw and having a recess providing clearance for the water projected from said grooves.

40 8. A spray head for lawn sprinkling systems and the like comprising a body having an outwardly flaring conical seat, an annular cap secured to said body having one edge thereof engaging said seat in line contact only, said seat being provided with a series of circumferentially spaced open-sided grooves.

45 9. A spray head for lawn sprinkling systems and the like comprising a body having an outwardly flaring conical seat, means for whirling the water within the spray head around the axis of said conical seat, said seat having a series of circumferentially spaced open-sided grooves

50 formed therein and an annular cap secured to said body having one edge thereof engaging said seat in a circular line contact.

10 10. A spray head for lawn sprinkling systems and the like comprising a body having an outwardly flaring conical seat, one segmental portion of said seat being provided with a series of circumferentially spaced grooves and another portion being ungrooved and an annular cap secured to said body having one edge thereof engaging said seat in a circular line contact only thereby forming a seal with the ungrooved portion of said seat and forming means for breaking up the streams projected from said grooves.

15 11. A spray head for lawn sprinkling systems and the like comprising a body having an outwardly flaring conical seat, means for whirling water within said spray head around the axis of said seat, said seat being provided with a series of circumferentially spaced laterally extending grooves extending substantially to the point where the water leaves the spray head for projecting the water in a series of separate streams, said grooves being inclined in the opposite direction from the direction of whirl to break up said streams and an annular cap having one edge thereof engaging said seat in a circular line contact.

20 12. A spray head for lawn sprinkling systems and the like comprising a body having a series of circumferentially spaced serrations for projecting the water, said body having an annular inner surface, a stationary core within said body having its outer surface seating in said annular inner surface forming a chamber between said core and said serrations, said core having inclined grooves in said outer surface for supplying whirling water to said chamber.

25 13. A spray head for lawn sprinkling systems and the like adapted to obtain uniform distribution with a predetermined water pressure comprising a body, means for whirling the water in said body and means extending substantially to the point where the water leaves the spray head for forming the water into a series of separate streams inclined with respect to the direction of whirl in accordance with said predetermined pressure, said inclination ranging from an angle of 30° in the opposite direction to the whirl in the case of extremely low pressures to an angle of 30° in the same direction as the whirl in the case of high pressures.

30 14. The method of lawn sprinkling to obtain uniform distribution with a predetermined water pressure supply which comprises internally whirling the water and discharging the water in a series of streams substantially at the point where the water leaves the spray head and inclining said streams with respect to the direction of whirl in accordance with said predetermined pressure, said inclination ranging from an angle of 30° in the opposite direction to the whirl in the case of extremely low pressures to an angle of 30° in the same direction as the whirl in the case of high pressures.

35 15. A spray head for lawn sprinkling systems comprising a body having a seat, a cap secured to said body having annular contact with the seat, said seat being provided with circumferentially spaced grooves extending beyond the annular line of contact in the direction of spray.

40 16. A spray head for lawn sprinkling systems comprising a body having a seat provided with circumferentially spaced grooves, a cap having

annular contact with said seat, but leaving a portion of each groove open sided.

17. A spray head comprising a body and a cap, said body being provided with circumferentially spaced conically diverging grooves, the body and cap having annular contact across said grooves less in width than the length of the grooves.

18. A spray head comprising a body member with a seat, and a conical cap member wider than said seat, said body member being provided with circumferentially spaced conically diverging grooves, the other forming with the grooves a series of orifices.

19. A spray head having a member fashioned to receive fluid under pressure and having an opening through the upper end thereof, a cap member for said opening, means providing for the discharge of fluid through the opening including a conical seat on one of the members formed with a plurality of circumferentially spaced serrations across the same, said serrations extending substantially to the point where the water leaves the spray head, and an annular edge on the other of said members having annular contact narrower than the width of the seat to form with the serrations a plurality of orifices arranged to discharge unobstructed streams.

20. A lawn sprinkler head comprising a body and a cap, one of which is provided with circumferentially spaced conically diverging grooves, the body and cap having annular line contact across said grooves.

21. A lawn sprinkler head comprising a body member with a seat, and a conical cap member wider than said seat, one of said members being provided with circumferentially spaced conically

diverging grooves, the other forming with the grooves a series of orifices, said cap and seat having substantially annular line contact.

22. A lawn sprinkler head comprising a body having an outwardly flaring seat, an annular cap secured to said body and engaging said seat in annular line contact only, one of said members being provided with circumferentially spaced conically diverging grooves and the other forming with the grooves a series of orifices.

23. In a lawn sprinkling system, an upwardly directed spray head comprising two contacting members, one of which has a series of circumferentially spaced conically diverging grooves extending at an angle not substantially greater than 45° to the horizontal, one of said contacting members extending beyond its contact with the other while remaining in contact with the streams from said grooves whereby the water is distributed over the area within the range of said streams.

24. In a lawn sprinkling system, an upwardly directed spray head comprising two contacting members, one of which has a single series of circumferentially spaced conically diverging grooves extending at an angle not substantially greater than 45° to the horizontal, substantially all of said grooves extending at the same inclination, and substantially all of the water being discharged through said single series of grooves, one of said contacting members extending beyond its contact with the other while remaining in contact with the streams from said grooves whereby the water is distributed over the area within the range of said streams.

ELMER G. MUNZ.
